Fig. 2.

Diagram illustrating a 6-pulse converter circuit with a common-emitter (CE) output stage. The circuit includes six main thyristors (TC1-TC6) and their associated control and protection circuits. A detailed view of the first pulse is provided, showing the timing of the triggering signals (td1, td2, td3, td4, td5, td6) and the control signals (a1, a2, a3, a4, a5, a6). The circuit includes a common-emitter output stage with transistors A and D, and a feedback loop with a motor ZM and a tachometer TDM.

ELECTROMAGNETIC SWITCH

Application filed September 21, 1931, Serial No. 563,953, and in Great Britain October 8, 1930.

This invention relates to electro-magnetic switches of the kind used in automatic telephone systems and has in view means whereby any one of a comparatively large number 5 of incoming circuits may be connected to any one of a comparatively large number of outgoing circuits in a simple and economical manner.

In the present invention we provide a 10 switch comprising a plurality of sets of wipers and associated contact banks the wipers being movable by a common motive means and arranged so that in their stepping the wipers of the several sets occupy different 15 relative positions as regards one another at each complete passage over a group of contacts in a bank, the corresponding wipers of the several sets being connected together either directly or indirectly.

20 The invention admits of several embodiments.

In one embodiment the wipers of one set are advanced one step for each complete passage by another wiper set over a group of 25 associated bank contacts. For example, the switch may comprise two sets of rotating wipers and associated bank contacts. Each wiper set may be assembled as a unit, the two 30 units being mounted on rotatable members in line, one of the members being rotated by a pawl and ratchet mechanism as in known arrangements, the other member being driven from the first by any suitable means so that its wipers are advanced one step after the 35 first set has passed over a given number of fixed contacts.

In another embodiment the wipers of each set are adapted to be stepped simultaneously, the stepping being so arranged that after a 40 complete passage by one wiper set over a group of associated bank contacts another wiper set lags behind the first mentioned wiper set by one or more contacts, the lag increasing at each complete passage over a 45 group of contacts by the first mentioned wiper set. As an example of this embodiment the following arrangement may be employed. Two wiper sets are mounted on separate rotatable members as in the previous 50 example, each set having a ratchet, the two

ratchets being engaged by a common pawl or pawls suitably connected. One ratchet has a different number of teeth to the other whereby after the passage by one wiper set over a given number of contacts subtending a particular angle the other wiper set has passed over a similar number of contacts subtending a different angle. It may be arranged that there is a certain amount of lost motion in the engagement of the pawl with 55 one of the ratchets so that at each step the ratchets are moved through different angular distances.

The ratchets may be of different diameters in which case the ratchets will move for the 60 whole stroke of the pawl but at different angular speeds.

Alternatively the ratchets may be of the 65 same diameter and be engaged by projections on the pawl which make different strokes.

70 Switches according to the invention may be employed for interconnecting purposes in an automatic telephone system.

A switch of the kind above described may be arranged as a backward and forward 75 hunting pair, one set of wipers being employed for backward hunting and the other set for forward hunting or selecting. A number of such switches may be assembled for backward hunting over the same multiple, the contacts associated with the forward selecting wipers being connected to different links. The outlets of each forward selecting switch may comprise a group 80 of links. Outlets of forward selecting 85 switches of other groups of similar switch pairs may be multiplied in the group of links, the backward hunting parts of the switches being associated with other multiplied inlets.

These groups of links may be connected 90 directly to outgoing links such as links to different groups of numerical selecting switches or further groups of backward and forward hunting switches may be connected 95 between groups of links and the outgoing links to further apparatus. The backward hunting switches of these further groups may each operate on a group of links, the outlets of the forward selecting switches of a group 100

being multiplied to a group of outlets to further apparatus.

The outlets from the forward selecting switches associated with further apparatus 5 may be graded in a suitable manner and additional pairs of switches may be added for the purpose of increasing the accessibility of any group of outgoing links.

The selection of a particular route for a 10 connection may be accomplished in any convenient manner such as by the use of a common bypass or marking arrangement responsive to impulses and used only during the setting up of a connection.

15 For the better understanding of the invention reference will now be had to the accompanying drawings in which Figs. 1 and 2 show one form of driving mechanism for a rotary selecting switch embodying the 20 invention, and Fig. 3 a modification. These drawings show only sufficient of the driving mechanism for the understanding of the invention the assembly of the switch wipers and banks following a well known form. 25 Figs. 4 and 5 show diagrammatically how switches according to the invention may be employed to interconnect any one of a number of inlets to any one of a number of outlets. Figs. 6 and 7 show circuit arrangements for the interconnecting scheme shown 30 in Fig. 4. The switches are of the type in which when one wiper of a set leaves one end of a bank another wiper of the set is stepped into the bank at the other end.

35 In Fig. 1 a mounting plate 1 is provided with extensions 2 which provide bearings for wiper shafts 3 and 15 and support the bank of contacts indicated in dotted lines at 4. Mounted on plate 1 is the driving magnet 5 40 having armature 6 carrying extension 7 to which is secured a double pawl member 8 having two pawls 9 and 10. A return spring 11 stretching between a projection on the armature extension 7 and a suitable pin or 45 stop 12 provides for the quick return of the armature when the magnet is de-energized. The pawls 9 and 10 engage respectively ratchets 13 and 14 of different diameters and having different numbers of teeth. Ratchet 50 13 is mounted on shaft 3 to which is secured a set of wipers co-acting with one bank of contacts and ratchet 14 is mounted on shaft 15 to which is secured another set of wipers co-acting with a different bank of contacts.

55 The number of teeth in the two banks are so arranged that for one complete traverse of the banks one wiper set takes a greater number of steps than the other, there being one more contact position in the bank associated with the wipers on shaft 3 than in the bank associated with the wipers on shaft 15. 60

When the magnet is energized both pawls engage the ratchets and each ratchet is rotated one step. If there are, for example 10 65 contact positions in the bank associated with

the wipers on shafts 15 and 11 in the bank associated with the wipers on shaft 3 then after the magnet 5 has been energized and de-energized 10 times each wiper set would be in contact with the 10th bank contacts. 70 On the next step the wiper set on shaft 15 is stepped off the 10th contact and again makes contact with the first contact in the bank while the wiper set on shaft 3 is stepped from the 10th to the 11th contacts. The 75 11th contacts are disconnected so that on the first rotation of the wipers from the position where both wiper sets rest on the first contacts each contact in one bank is put into contact with corresponding contacts in the 80 other bank. When the wipers on shaft 3 are stepped onto contact 11 no connection is made with contact 1 in the other bank but at the next step the wipers on shaft 3 are stepped from the 11th contact and are brought 85 into contact again with contact 1. Contact 2 in one bank is now connected to contact 1 in the other bank and the wipers are rotated again until the wipers on shaft 3 reach the 90 11th contacts. During this rotation the contacts in one bank are put into connection with the contacts in the other bank but this time the interconnection by the wipers at any moment is between different pairs of contact sets from the interconnection made 95 during the first rotation. When contact 10 is reached by one set of wipers the other set is again on contact 1 so that when the former set steps to contact 11 and then again to 1 the latter set steps to 2 and then to 3 and 100 there is a difference of two contact positions between the positions of the two wiper sets at any moment. By continued rotation in this manner the number of contact positions between the positions occupied by the wiper sets is increased by one at each complete 105 traverse of the banks and after 10 complete traverses forming a cycle both wipers are stepped onto their contacts 1 at the same time. It will be seen that during this cycle 110 each contact in one bank has been put into connection with each contact in the other bank once.

115 It will be readily seen that instead of making the ratchets of different diameters I may make them the same diameter but provided with teeth of different pitch so as to produce a different angular displacement between the wiper sets after one complete traverse of the bank. In the case assumed it would be arranged that one wiper set requires one more step to traverse the same angle than does the other wiper set. The magnet armature may be connected to a common member connected to two pawls which engage teeth on the two 120 ratchets. In order to step both ratchets a full step at each operation of the driving magnet the strokes of the pawls must be different and this may be attained by forming one pawl as a projection from and shorter 125

than the other so that as regards the short pawl there is a period of lost motion at each stroke equal to the difference in pitch of the teeth on the two ratchets.

5 Fig. 3 shows a modification of the driving arrangements in which one set of wipers is advanced one step after each complete traverse of its bank by the other set. This type of mechanism is well known in connection with 10 counting mechanisms to produce decimal rotation. In this figure the driving mechanism only is shown diagrammatically. The ratchet 13 is secured to shaft 3 which carries one set of wipers and is stepped by means of 15 the pawl 8. The ratchet 14 is secured to shaft 15 and carries another set of wipers. On a spindle parallel to shaft 15 is mounted a pinion 16 engaging with the teeth of ratchet 20 14 and adapted to be rotated by a cam 17 carried by shaft 3. The cam is so arranged that after one complete traverse of its banks by the wipers on shaft 3 the pinion 16 is engaged and rotated a quarter turn thereby 25 rotating ratchet 14 to advance the wipers on shaft 15 one step. This ratchet is stepped in a similar manner after each complete traverse of its bank by the wiper set on shaft 3 so that each contact in one bank is put into 30 connection once with each contact in the other bank during a complete cycle of operations.

Reference will now be made to the diagrammatic arrangement shown in Fig. 4. At a 35 switching stage a number of switches form a panel and a number of panels are provided, links incoming from a preceding switching stage being connected to the multiple of a panel. In the figure are shown two panels 40 only A and B at a switching stage and three switches per panel. The switches are of the type previously described and will be referred to as first couplers. A switch comprises two sets of wipers designated *a* and *p* 45 respectively. A set comprises the speaking and test wipers and a control wiper or wipers as required, each set being associated with a bank of contacts the wipers, or some of them, of a set being adapted to be put into 50 direct electrical contact with corresponding wipers of the other set. The switches associated with panel A are designated AFC1, AFC2 and AFC3; and those associated with 55 panel B are designated BFC1, BFC2 and BFC3. The wipers *a* of a switch are associated with contacts of the panel multiple while the wipers *p* are associated with contacts of groups of links multiplied over 60 contacts wiped by similar wipers of corresponding switches in other panels. Thus wipers *a* of switches AFC1, AFC2 and AFC3 are associated with contacts connected to the panel multiple while wipers *p* of switches AFC1 65 and BFC1 are associated with contacts con-

nected to a group of links LC1. A coupler hunts in two directions, the switch acting as a backward hunting switch with its wipers *a* and as a forward hunting switch with its wipers *p*.

Similar switches to be referred to as second couplers are provided which act in a similar manner. A second coupler acts as a backward hunting switch with its wipers *a* which co-act with contacts connected to a group of multiplied links and as a forward hunting switch with its wipers *p* which co-act with contacts connected to a group of multiplied outlets. Of these second couplers those designated XSC1, XSC2 and XSC3 are associated with a group of outlets X, and groups of multiplied links. Similarly those designated YSC1, YSC2 and YSC3 are associated with a group of outlets Y and the same groups of multiplied links. The wipers *a* of a second coupler with which it acts as a backward hunting switch are associated with a group of links and more particularly these wipers of switches XSC1 and YSC1 are associated with contacts connected to a group of links LC1 which group is as stated above multiplied also over contacts of first couplers, while wipers *p* with which a second coupler acts as a forward hunting switch are associated with the groups of outlets and more particularly these wipers of switches XSC1, XSC2 and XSC3 are associated with contacts connected to outlets multiplied over other switches in the group X. The corresponding wipers *p* of couplers YSC1, YSC2 and YSC3 co-act with contacts similarly connected and multiplied over the group of outlets Y.

In order to set up a connection from an incoming link, such as, for example, one connected in panel A to an outlet, such as, for example, one connected in the group Y, a first coupler is first taken into use. This may be the coupler AFC1 and it is rotated in search of the calling incoming link. When this is found a test is made at the same time for a free link in the group LC1 and rotation continues until the switch is stepped on to the calling link with one set of wipers and at the same time the other set is stepped on to contacts connected to a free link. A second coupler having access to the group Y which may be that designated YSC1 is then started to hunt with one set of wipers for the link in the group LC1 seized by the coupler AFC1 and with the other set for a free outlet in the group Y, rotation of the switch continuing until both the marked link and a free outlet have been found. The couplers are taken into use by a control switch not shown in this figure which selects a free second coupler having access to the desired group of outlets which latter is determined by impulses received by the control switch. A further requirement has to be met in that a free group of links over which the couplers are to be 130

- connected must be found. This may be done by marking a link from the control switch or arranging that links in a group are marked free and available one at a time by suitable means. Circuit arrangements for setting up a connection over switches diagrammatically represented to this figure are shown in Figs. 6 and 7 and will be referred to later.
- 10 As even distribution of traffic over the links is unlikely grading of the outlets of the second coupler may be resorted to in order to increase the availability.
- 15 In Fig. 5 is shown an arrangement of first couplers and links similar to that shown in Fig. 4 but no second couplers are provided. In this case the links in a group are connected directly to outlets. In the example shown outlets of group 1 are connected to the first 20 links in each group of links, outlets of group 2 to the second links of each group of links and so on, the links in the group LC1 being connected to outlets in different groups. In this case the control switch receives impulses 25 for determining the group of outlets in which connection is to be made and searches for a coupler having access to the calling incoming link and for a free link to the desired group.
- 30 In order to deal with unevenly distributed traffic it may be arranged that couplers serving a panel are taken into use in a definite order and that the first choice couplers give access to first choice links. Grading may be 35 employed whereby the earlier choice couplers have access to individual links and later choice couplers have common access to links.
- 40 Figs. 6 and 7 will now be referred to. Fig. 6 shows a first coupler FC, adapted to connect incoming links in a panel A to a link in a group of links LC and a second coupler SC adapted to connect links in the group LC to outlets in the group X, while Fig. 7 which is intended to be placed below Fig. 6, shows a 45 control switch CS available in common to a panel adapted to select, in response to impulses, couplers having access to the calling line and to the desired group of outlets.
- 50 The control switch CS is of the ordinary two motion type with 6 wipers and corresponding contact banks. It is controlled by an impulse relay A, a dialling relay D and test relay TC. Its magnets are designated VM, RM and ZM for the vertical, rotary 55 and release magnets respectively. The couplers are unidirectional rotary switches, each being provided with 8 wipers and corresponding contact banks. The first coupler magnet is designated DFM and the switching relay 60 TF, and the second coupler magnet and switching relay are designated DSM and TS respectively. A coupler in its function as a backward hunting switch employs wipers a, b, c, d and in its function as a forward 65 hunting switch employs wipers p, q, r, s.

The arrangement shown is assumed to be connected in a system in which the dialled impulses are recorded on a register which retransmits them over the b wire to the several switching stages and in which retransmission 70 from the register may be held up by the connection at a switching stage of battery on the a wire.

A preceding switch tests in over wire c, contact k2 of relay K and if the control switch is 75 free contact a2 will be open. When the link is seized earth is connected to wire p at the preceding switching stage and relay T operates from earth on wire p over contact k4, winding of relay T, contacts t1, a1 to battery. Contact t1 which is of the make before break type connects winding (I) of relay X in series with relay T and contact t2 connects earth on wire c to contact a2 which on operation of relay A extends this earth over vertical off-normal contact n1 of control switch CS to slow releasing dialling relay D. Contact t5 marks the bank of wiper d of the coupler FC; contacts t4 and t6 connect the incoming a and b wires to the control switch circuit, 80 the circuit over wire b including relay A of the control switch, and contact t3 connects the wire c to the contacts in the bank of wiper c.

85 Relay A now operates from battery connected to the b wire in the register circuit and opens its contact a1 to guard vertical magnet VM against a false impulse. Contact a2 closes the circuit for relay D, contact a3 opens a point in the circuit of the release magnet and closes a point in that of the rotary magnet, and contact a4 prepares the test circuit for relay TC. Relay D operates and at contact d1 prepares a holding circuit for itself 90 during impulsion, and at contact d2 prepares the vertical magnet circuit for impulses.

95 Relay X, which operates after relay T, prepares a holding circuit for itself at contact a3 and at contact a2 connects earth to all the wires c incoming to the panel to prevent any other link incoming to the panel being seized until the control switch has been restored and is available to deal with another call. Contact a1 opens the operating circuit of relay T. The train of impulses for extending the connection at this switching stage is now received 100 from the register and relay A responds to it, repeating the impulses at contact a1 to vertical magnet VM which steps the wipers of switch CS to a level containing outlets in the desired group denoted by the number of impulses transmitted to it. This group contains the outlets X multiplied to second couplers SC. At the first vertical step the vertical off-normal contacts are operated, contact n1 opening the operating circuit of relay D and completing the holding circuit for that relay, contact n2 preparing the rotary magnet circuit, and contact n3 closing the holding circuit for relay X over its winding (II). At 110 the end of the impulse train relay A remains 115

120

125

130

steadily operated and relay D releases. Contact d_1 opens to prevent re-operation of relay D and contact d_2 closes the circuit for the rotary magnet RM which is intermittently energized by means of the interrupter in its circuit. The wipers are rotated around the level opposite to which they have been stepped in search of a free first coupler denoted by earth over contacts gp , tf_4 and wiper 1 of switch CS and of a free second coupler denoted by absence of earth over wiper 2 of switch CS, the coupler searched for being associated with the same group of links. These correspond for example to couplers AFC1 and XSC1 associated with links LC1 in Fig. 4.

It should be explained that a relay GP is provided common to all first couplers having access to a group of links such as for example the couplers AFC1 and BFC1 in Fig. 4 and the relay has a contact gp in each coupler circuit FC. As soon as a first coupler is taken into use relay GP is operated and by opening its contacts gp ensures that only one link in a group such as LC1 (Fig. 4) is marked for search at a time, other control switches being prevented at this time from taking into use couplers having access to this particular group of links. This will be readily understood by inspection of Fig. 4.

It being assumed that the coupler FC is free and that relay GP is not operated relay TC will operate if the coupler SC is likewise free. Search by switch CS continues until a pair of couplers connected to the same group of links is free whereupon relay TC not being short circuited by earth over wiper 2 but finding earth over wiper 1 operates and opens the circuit of magnet RM at contact tc_3 . Contact tc_2 connects earth to wiper 2 to mark the second coupler SC engaged and contact tc_4 connects earth to wiper 3 to operate relay RF in the first coupler FC and the relay GP. Relay GP operates and opens the test circuits of all the couplers having access to the link LC at its contacts gp but relay TC continues to hold by means of its winding (II) over contacts tc_1 , t_2 and wire c . Contact tc_5 operates relay TD and contact tc_6 disconnects relay A. Relay TD operating contact td_1 connects battery over contact t_6 to the incoming a wire to hold up impulsion at the register, contact td_2 prepares a circuit for relay K and contacts td_3 , td_4 and td_5 connect up wipers 4, 5 and 6 of switch CS.

In the first coupler relay RF has operated. Contacts rf_1 and rf_2 connect up the test circuit of relay TF and contact rf_3 closes the circuit of the coupler magnet DFM. Magnet DFM is now intermittently energized by means of the interrupter and drives the wipers round until wipers p , q , r , s are stepped on to a free link LC at the same time as wipers a , b , c , d are stepped on to contacts of the marked incoming link. A

free link LC is denoted by absence of earth on the contact in the bank of wiper r , and the marked incoming line by the connection of earth over contact t_5 to the bank of wiper d . When these conditions are met relay TF operates over its winding (I) and locks up over its winding (II) and contact tf_1 , wiper c , contact t_3 and wire c to earth. Contact tf_2 opens the circuit of magnet DFM, contacts tf_3 , tf_5 and tf_6 connect wipers a , b and c through to wipers p , q and r , and contact tf_3 disconnects winding (I) of relay TF from wiper r . Contact tf_4 opens in the test circuit of switch CS against release of relay GP and contact tf_7 connects earth over wiper 5 and contact td_4 to relay EF. Relay EF operates and at contact ef_1 connects earth over contact td_3 and wiper 4 to relay RS. Relay RS operates and at contacts rs_1 and rs_2 prepares testing circuits for relay TS and at contact rs_3 closes the circuit of magnet DSM of the second coupler. The magnet is operated intermittently by means of the interrupter in its circuit and rotates the wipers of the second coupler until its wipers p , q , r , s are stepped on to contacts of a free outlet at the same time as its wipers a , b , c , d are stepped on to contacts of the link seized by the first coupler. The test for a free outlet is absence of earth over wiper r and contacts ts_3 and rs_1 while the link seized by the first coupler is marked by earth over contact rf_4 and wiper s of coupler FC. When the above conditions are met relay TS operates over its winding (I) wiper d of coupler SC, the link LC, wiper s of coupler FC, contact rf_4 to earth. Relay TS locks up over its winding (II) contact ts_1 , wiper c of coupler SC, the link LC, to the c wire and opens the circuit of magnet DSM at contact ts_2 . Contact ts_3 disconnects winding (I) of relay TS from wiper r of coupler SC, contacts ts_5 and ts_6 switch the a and b wires through, contact ts_4 connects earth to the contact in the bank of wiper 2 of switch CS to mark the coupler engaged and contact ts_7 connects earth over wiper 6 of switch CS to operate relay ES. Contact ts_8 connects earth over wiper s to take into use the control switch in the next switching stage. Contact es_1 connects earth over contacts td_2 and t_7 , to winding (I) of relay K which thereupon operates and locks up over its winding (II) and contacts k_1 to wire p . Contact k_2 disconnects earth over contact x_2 in the control circuit from the incoming wire c , contact k_3 closes in parallel with contact t_3 which will shortly be opened, and contact k_4 opens the circuit of relay T and winding (I) of relay X. Relay T releases and disconnects the control circuit from the incoming link, contact t_2 opening the locking circuit of relay TC, contact t_4 opening the circuit of relay A, contact t_6 disconnecting battery from wire a thereby al-

lowing impulsion from the register to re-commence, and contact $t7$ opening the operating circuit of relay K. Relays A, TC and TD release. A circuit is now closed from 5 earth over contacts $tc3$, $d2$, $n2$, $a3$, magnet ZM to battery. The magnet operates and releases the switch CS to normal whereupon the off-normal contacts are restored and the release magnet circuit opened at contact $n2$. 10 Contact $n3$ opening, relay X releases and battery is again connected to the other incoming wires p of the panel and the busy marking on other incoming wires c is removed by the opening of contact $x2$. The release of relay 15 TD releases relays EF and ES and by the opening of contacts $tc4$ and $td3$ relays RF and RS are released.

The remainder of the connection is set up by further trains of impulses received at 20 subsequent switching stages which may be similar to that shown in Figs. 6 and 7.

The connection is released by the disconnection of earth from wire c at the point where the feeding bridge is situated resulting in the release of relays TF and TS and, 25 by the disconnection of earth from wire p by a contact similar to $ts8$, relay K is released. The opening of contact $ts8$ disconnects earth from wiper s thereby releasing relay K in the 30 next switching stage.

In an alternative arrangement that may be employed the control switch in addition to searching for a pair of couplers having access to the calling line and the wanted group 35 searches for a free link between two couplers. When the link and a pair of free couplers are found the control switch is brought to rest and marks the link for which the two couplers may then search simultaneously, the whole 40 group of links being marked busy to other control switches while the couplers are searching for the marked link. In order to avoid complicated group control arrangements and to simplify the control switch a distributor 45 switch may be provided for each group of links which is always set on contacts of a free link. A number of distributor switches, each having access to a different group of links could be provided and would be available in 50 common to all the control switches having access to the groups of links. A control switch would then search for a free distributor switch which on being found is seized and applies a busy marking on the link on which 55 it is standing which link is then searched for by the couplers seized by the control switch.

In a switch of the kind described it will be clear that if the number of contact positions in one bank exceeds that in the other bank 60 by one each contact in one bank will be put into connection once with each contact in the other bank during a cycle of transverses of the switch banks. The number of contact positions in the two banks may however differ by more than one provided the difference 65

is not a sub-multiple of the number of contacts in the smaller bank.

I claim:

1. In an automatic switch, two sets of wipers, two banks associated with said two sets of wipers, respectively, each bank comprising a plurality of sets of bank contacts, common driving means for said wiper sets, and means controlled by said driving means for moving said wiper sets to connect each set of contacts in one bank to every set of contacts in the other bank. 75

2. In an automatic switch, two sets of wipers, two banks associated with said two sets of wipers, respectively, each bank comprising a plurality of sets of bank contacts, a stepping magnet common to both sets of wipers, and means controlled by said stepping magnet for rotating said wiper sets over their respective bank contacts, said means including separate rotating arrangements for each wiper set so that by continued operation of said stepping magnet each contact set in one bank will be connected to every contact set in the other bank through said wiper sets. 85

3. In an automatic switch, two wiper sets, two banks associated with said two wiper sets, respectively, each bank comprising a plurality of contact sets, one bank containing a greater number of contact sets than the other, a stepping magnet, and separate means controlled by said stepping magnet for moving said wiper sets over their respective bank contacts step by step, whereby each contact set in one bank is connected to every contact set in the other bank through said wipers by continued operation of said magnet. 95

4. In an automatic switch, two sets of wipers and associated banks, a common operating magnet, and a separate ratchet and pawl for each wiper set controlled by said magnet whereby one wiper set is rotated through a greater angle than the other for each operation of said magnet. 105

5. In an automatic switch, two shafts each mounting a set of wipers, a bank associated with each set of wipers, a ratchet on each shaft, one ratchet having a greater number of teeth than the other, two pawls for engaging said ratchets, respectively, and a common driving magnet for operating said two pawls. 110

6. In an automatic stepping switch, two sets of wipers, two banks associated with said two sets of wipers, respectively, a magnet, means controlled by said magnet for rotating one set of wipers over its bank, and means for rotating the other set of wipers one step each time said first set has completely traversed its bank. 120

7. In an automatic stepping switch, two sets of wipers, two banks associated with said two sets of wipers, respectively, a magnet, means controlled by said magnet for rotating one set of wipers step by step over its bank, and means controlled by the rotation of said 125

130

- first set of wipers for rotating the other set of wipers one step each time said first set has been rotated a predetermined plurality of steps.
8. In a telephone system, a plurality of stepping switches, each switch having two sets of wipers and two banks respectively associated therewith, a plurality of incoming trunks connected in multiple to one bank of each of said switches, and a plurality of groups of outgoing links, each group being connected to the other bank of different one of said switches.
9. In a telephone system, two groups of stepping switches, each switch having two sets of wipers and two banks respectively associated therewith, two groups of incoming trunks, one group multiplied to the first banks of one group of switches and the other group multiplied to the first banks of the other group of switches, and a plurality of groups of outgoing links equal in number to the number of switches in each of said groups of switches, each group of links being multiplied to the second banks of a switch in each group of switches.
10. In a telephone system, a stepping switch having two sets of wipers and two banks respectively associated therewith, a plurality of incoming trunks connected to one bank and a plurality of outgoing trunks connected to the other bank, means for marking one of said incoming trunks to indicate a calling condition on said trunk, common driving means for said sets of wipers, and means for controlling said driving means to rotate said sets of wipers until the first set connects with the marked trunk and the second set simultaneously connects with an idle outgoing trunk.
11. In a telephone system, a stepping switch having two sets of wipers operated by the same driving means, one set of wipers having access to incoming trunks and the other set having access to outgoing trunks, means for marking one of said incoming trunks, a relay in said switch for rendering said driving means inoperative, and means for operating said relay responsive only to the simultaneous connection of the first set of wipers with said marked trunk and of the second set of wipers with an idle one of said outgoing trunks.
12. In a telephone system, a plurality of stepping switches each having two sets of wipers, the first set of each switch having access to the same group of incoming trunks and the second set of each switch having access to a different group of outgoing trunks, a control switch common to said incoming trunks, means responsive to the operation of said control switch by a dialled digit received over one of said incoming trunks for seizing an idle stepping switch having access to the desired group of outgoing trunks as indicated by the value of the received digit, a single driving magnet rotating both sets of wipers of the seized stepping switch, and means for stopping said switch responsive to the simultaneous connection of one set of wipers with the calling incoming trunk and of the other set of wipers with an idle outgoing trunk in the desired group.
13. In a telephone system, a plurality of incoming trunks, a plurality of groups of outgoing trunks, a plurality of switches having two sets of wipers for interconnecting incoming and outgoing trunks, means common to said incoming trunks and controlled over a calling one of said trunks for selecting an idle switch having access to the calling trunk and to the desired group of outgoing trunks, and means for operating the selected switch to connect the calling trunk with an idle outgoing trunk in the desired group by means of said sets of wipers, said means including a single driving magnet for operating both sets of wipers.
14. In a telephone system, a group of incoming trunks, a plurality of groups of outgoing trunks, a plurality of groups of links, a group of switches having access to said group of incoming trunks and said groups of links, a second group of switches having access to said groups of links and to said groups of outgoing trunks, means controlled over a calling incoming trunk for simultaneously selecting a switch in the first group having access to the calling trunk and to one group of links and a switch in the second group having access to the same group of links and to the desired group of outgoing trunks, and means for automatically operating the selected switches to complete a connection from the calling trunk to an idle trunk in the desired group of outgoing trunks.
15. In a telephone system, a group of incoming trunks, a plurality of groups of outgoing trunks, a plurality of groups of links, a group of switches having access to said group of incoming trunks and to said groups of links, a second group of switches having access to said groups of links and said groups of outgoing trunks, means responsive to a digit received over a calling one of said incoming trunks for selecting an idle switch in the first group having access to the calling trunk and to one group of links and an idle switch in the second group having access to the same group of links and to the desired group of outgoing trunks as indicated by the value of the received digit, and means for automatically operating said first switch to connect the calling trunk with an idle link and for automatically operating said second switch to connect the link seized by said first switch with an idle trunk in the desired group of outgoing trunks.

In testimony whereof I affix my signature.
DAVID ADAM CHRISTIAN. 130
